Inventor:
Waldemar Kroll,
by his Attorneys-
Houwon & Houwon

UNITED STATES PATENT OFFICE.

WALDEMAR KROLL, OF PHILADELPHIA, PENNSYLVANIA, ASSIGNOR, BY MESNE ASSIGNMENTS, TO THE YALE & TOWNE MANUFACTURING COMPANY, OF STAMFORD, CONNECTICUT, A CORPORATION OF CONNECTICUT.

SEALED PADLOCK.

Application filed July 1, 1925. Serial No. 40,867.

One object of my invention is to provide a padlock with a seal that will close the key opening in the lock, the lock being so designed that the key cannot be withdrawn 5 from the lock until the shackle of the lock is closed and is engaged by the bolt.

Another object of the invention is to prevent the opening of the lock and the withdrawal of the key and the appliance of the 10 seal to the open lock.

In the accompanying drawings:

Fig. 1 is a perspective view of my improved sealed padlock, showing the seal in position and the shackle closed;

15 Fig. 2 is a sectional view of a lock to which my invention is applied; the shackle being open; and

Fig. 3 is an end view of the lock partly broken away.

20 My invention is used in connection with a lock for which patent was granted to Frank Soley April 26, 1910, No. 956,213.

Referring to the drawings, 1 is the casing of the lock. 2 is the shackle, which is pivoted to the casing at 3. 4 is a key pin. 5 is a bolt for engaging the nose of the shackle. 6 is a sliding member, which has an extension 7 that encircles the key pin 4. The key 8 is mounted on the pin 4, as shown in Fig. 3, and when the shackle is in the open position, as illustrated in Figs. 2 and 3, it is held within the lock by the encircling member 7. The key cannot be removed until the shackle 2 is closed and the bolt 5 is in engagement therewith. When the parts are in this position, the encircling member is moved clear of the key so that the key can be withdrawn clear of the lock.

Encircling the key opening of the padlock is a plate 10, which has a key opening 11 40 that coincides with the opening in the body of the lock. In this plate is a channel 12 for the passage of the sealing strip 13. This sealing strip extends around the body of the lock, as illustrated in Fig. 1, and the two 45 ends of the strip are united by a seal 14. This sealing strip closes the key opening in the lock and prevents the manipulation of the lock by a key, or by a picking instrument. 50

In order to open the lock, the seal must be broken so that the proper key can be inserted in the lock. After the key is inserted and the shackle is disengaged from the locking mechanism, the key is retained in the 55 lock until the shackle is again closed and locked. This prevents the sealing of the lock until the shackle is closed and locked and also prevents the withdrawal of the key and the appliance of the seal to the open 60 lock. All tampering with the lock is absolutely impossible, as the lock must be closed before the seal can be applied.

I claim:

In a padlock, the combination with a casing having a key opening therein, of a shackle; a plate permanently attached to or forming part of the casing and encircling the key opening of the lock, said plate having a key opening coinciding with the key 65 opening of the lock, and having a channel 70 for a sealing strip; a sealing strip encircling the casing and extending through the channel; and a seal for attaching the two ends of the strip together.

WALDEMAR KROLL.
